ANTENNA LOBE SWITCHING SYSTEM

Janis A. Siron, Springfield, Ohio, assignor to the United States of America as represented by the Secretary of the Air Force

Application January 26, 1956, Serial No. 561,693

13 Claims. (Cl. 343—733)

(Granted under Title 35, U.S. Code (1952), sec. 266)

The invention described herein may be manufactured and used by or for the United States Government for governmental purposes without payment to me of any royalty thereon.

This invention relates to radio frequency switches and particularly to a switch for alternately connecting a coaxial transmission line to either of two other coaxial transmission lines carrying high frequency currents. It is an object of the invention to provide a radio frequency switch of this type that is capable of a relatively fast switching rate and that introduces a minimum of discontinuities in the transmission paths through the switch.

The switch finds particular utility as an antenna lobe switch in radio compass circuits such as disclosed and claimed in my application Serial No. 561,694, filed January 26, 1956. In this radio compass circuit a rhombic antenna is used as the directional receiving device and its field pattern is periodically switched from a directional pattern angularly displaced to one side of the antenna axis to a similar pattern equally displaced to the other side of the antenna axis. The pattern switching is accomplished by interchanging the feed and terminating points of the antenna. The circuit compares the outputs of the radio compass receiver, fed by the antenna, for each of the two conditions, and produces a direct current output having an amplitude directly related to the magnitude of the difference in the two receiver outputs and a polarity determined by the relative amplitudes of the two receiver outputs. The receiver output comparisons are accomplished by a phase sensitive detector which is synchronized with the antenna lobe switch by energizing both from a common source of alternating current. Further objects of the invention, therefore, are to provide an antenna lobe switch capable of periodically changing the feed and terminating points of a rhombic antenna and also capable of being driven by and in synchronism with a source of alternating current.

A more detailed description of the invention will be given in connection with the specific embodiments thereof shown in the accompanying drawings in which

Fig. 1 is a schematic diagram of the switch connected to a rhombic antenna;

Figs. 2 and 3 are plan and elevation views of one embodiment of the switch;

Figs. 4 and 5 are sectional views of the switch shown in Figs. 2 and 3;

Fig. 6 shows the details of the switch contacts;

Fig. 7 is an alternate driving mechanism for the switch; and

Fig. 8 is a time motion chart for the switch.

The antenna lobe switch and the manner of connecting it to a rhombic antenna are shown schematically in Fig. 1. In this figure, conductors 1, 2, 3 and 4 comprise a rhombic antenna. If point A is made the feed point and point B is terminated to ground through a proper terminating resistor, 50 ohms in the example shown, the field pattern of the antenna is as shown by the dashed line. If the feed and terminating points are now interchanged, the pattern becomes that shown in dotted outline. In radio compass circuits, signals received over the two patterns are compared to yield information as to the position of a source of radio signals relative to the

antenna axis perpendicular to the line A—B. The manner of accomplishing this comparison forms no part of the present invention and will not be discussed further. The switch shown schematically in Fig. 1 serves to periodically interchange the feed and terminating points of the rhombic antenna and operates at a relatively high rate, for example, 100 c./s. The switch comprises contacts 5 and 6 connected, respectively to points B and A of the antenna. The contact 7 is actuated by an electromagnetic drive generally illustrated by the armature 8 and coil 9. The armature 8 operates to move contact 7 in opposite directions during opposite half cycles of the energizing alternating current applied to coil 9. In the neutral position of the switch (coil 9 deenergized) contact 7 is in electrical connection with both contacts 5 and 6. Also contacts 10 and 11 make electrical connection with contacts 5 and 6, respectively. During operation, contact 7 is moved up and down by armature 8 periodically in synchronism with the energizing alternating current in coil 9. When contact 7 moves upward contacts 7—6 and 10—5 are broken, the latter by upward movement of contact 5. In this condition receiver 12 is connected to point B of the antenna through contacts 7—5 and point A of the antenna is connected to ground through contacts 6—11 and 50 ohm resistor 13. During the next half cycle of the alternating current in coil 9, armature 8 moves contact 7 downward opening contacts 7—5 and 6—11, the latter by pushing contact 6 downward. In this condition the receiver is connected to point A through contacts 7—6 and point B is connected to ground through contacts 5—10 and 50 ohm resistor 14.

The mechanical and electrical details of the lobe switch are shown in Figs. 2 to 6. Referring first to Fig. 4, this figure is a view taken along section line 4—4 of Fig. 2. Short sections of coaxial transmission line 15 and 16, terminating in coaxial connectors 17 and 18, enter opposite sides of switch contact housing block 19. The axes of these sections lie in a common vertical plane and their outer conductors extend to the center of block 19. Spring contacts 5 and 6, which may be made of beryllium copper, are extensions of center conductors 20 and 21 to which they may be attached by any method providing good electrical contact, such as by silver soldering. The construction of the spring contacts 5 and 6 is shown more clearly in Fig. 6. These contacts are preferably silver plated to increase surface conductivity. The free ends of spring contacts 5 and 6 overlap slightly and contact 7 is situated between the overlapping ends. The axes of coaxial sections 15 and 16 are vertically displaced by an amount sufficient to accommodate contact 7. Contacts 10 and 11 are in the form of metallic pins, preferably silver or silver plated, which extend into cavities in screw plugs 22 and 23 filled with a resistive material such as carbon. Plug 23 is shown in section and illustrates clearly the resistive filling 13 which forms the resistance 13 of Fig. 1, the body 19 being grounded. Resistor 14 is similarly provided in plug 22.

Means, to be explained later, are provided for moving contact 7 both up and down from the neutral position shown in Fig. 4 in a direction substantially normal to contacts 5 and 6. With contact 7 in its neutral position the switch is initially adjusted by screwing contact 10 up and contact 11 down until electrical contact is made with spring contacts 5 and 6 without breaking contacts 5—7 and 6—7. This is possible because of the initial spring bias in contacts 5 and 6 which causes the former to bow downward and the latter upward.

After proper adjustment of contacts 10 and 11 disturbance of the setting may be prevented by pouring sealing wax or other suitable compound in the space above the screw plugs 22 and 23. Also the screw caps

shown offer further protection against disturbance of the contact settings. Upward movement of contact 7 from its neutral position breaks contacts 6-7 and 5-10 while leaving contacts 5-7 and 6-11 closed. Downward movement breaks contacts 5-7 and 6-11 and leaves contacts 6-7 and 5-10 closed.

The details of contact 7 and the mechanism for oscillating it about its neutral position are shown in Fig. 5. The section shown in this figure is taken along section lines 5-5 of Fig. 2 and 5'-5' of Fig. 4. A third coaxial line section 24, terminating in coaxial connector 25, enters the block 19 in a direction normal to the directions of line sections 15 and 16. The cylindrical opening forming the outer conductor of this line section extends completely through block 19. Contact 7 is an extension of the center conductor of line section 24 to which it is attached through a short spring section 26. The spring 26 may be made of beryllium copper like spring contacts 5 and 6 and may be attached to contact 7 and center conductor 27 by means of silver solder. There should be no tension in spring 26 when contact 7 is in its neutral position, the nature of spring 26 being more that of a flexible coupling.

An electromagnetic drive is provided for oscillating contact 7 about its neutral position. This drive mechanism is contained in and supported by a housing 28 of nonmagnetic material to which block 19 is attached and with which it communicates through opening 29. The drive mechanism comprises a permanent magnet 30 held, together with pole pieces 31 and 32, between straps 33 and 34 of nonmagnetic material. Straps 33 and 34 are attached to each other by screws 35 and strap 33 supports the whole magnet assembly in housing 28 to which it is attached by screws 36. An armature 37, made of a material having high magnetic permeability, is attached to an angle member 38 by means of through-bolts 39 and plates 40 and 41 and the angle member is attached to housing 28 by screws 42. The angle member, which is preferably made of a nonmagnetic material of good elasticity such as beryllium copper, acts as a torsion support for the armature and effectively resists any movement of the armature other than movements producing torsion in the angle member. An advantage of the inherent stiffness of this type mounting is its well defined neutral position. The short end of the armature engages a slot 70 in an insulating cap 43 on contact 7.

The armature 37 is surrounded by a coil 44 which is suitably supported within the housing 28 as by wedges 45 and 46. Leads from the coil go to a gas-tight connector 47. Housing 28 is provided with a cover 48 (removed in Figs. 2 and 3). If the switch is to be evacuated or pressurized, it may be made gas-tight by soldering the cover to the housing body 28.

When an alternating current flows in coil 44, end 49 changes its magnetic polarity on each half-cycle of the alternating current. Since the magnetic polarity of poles 50 and 51 does not change, an alternate attraction and repulsion exists between each of these poles and the end 49 of armature 37 causing this end of the armature to vibrate in a vertical direction.

This oscillation is transmitted through the short end of armature 37 and coupling 43 to contact 7 causing it to oscillate about its neutral point and actuate the switch in the manner already described.

Another suitable driving mechanism for contact 7 of the switch is shown in Fig. 7. The operating principle is very similar to that of a permanent magnet electrodynamic loudspeaker. Permanent magnet 52 and circular yoke 53 operate to establish a strong magnetic field across the circular air gap between the lower end of magnet 52 and the circular pole piece 54 surrounding it. A coil of fine wire 55, wound on sleeve 56, is accurately positioned within the air gap with freedom of movement in the vertical direction. This is accomplished by two resilient diaphragm type mounts 57 and 58 which

are interconnected to move in unison by structural member 59 and spiders 60 and 61, the latter having sleeve 56 attached thereto. The member 59 also carries an insulating coupling 62 for transmitting its motion to contact 7. Resilient mountings 57 and 58 restrain member 59 from any motion other than in a vertical direction and resiliently oppose any movement of this member away from its neutral position in the vertical direction. When an alternating current is passed through coil 55 alternate up and down forces act on this coil which are transmitted to member 59 through sleeve 56. The resulting oscillation of member 59 about its neutral position is transmitted through coupling 62 to contact 7.

The spider 60 carries a weight 63 which may conveniently be made of solder. This weight is made such as to give the mass of the oscillating system the required value with respect to the resilience of mounts 57 and 58 to produce mechanical resonance at the frequency of the driving current in coil 55. The apparatus of Fig. 7 is also sealed and suitable for evacuation or pressurization of the switch.

In radio housing systems it is desirable that antenna lobe switching occur at a rate of at least 100 c./s. The switch described, with either the drive of Fig. 5 or that of Fig. 7, can easily attain this or higher rates. A time and motion chart of the switch contacts is shown in Fig. 8 for an operating frequency of 100 c./s.

I claim:

1. A switching device for coaxial transmission lines comprising first and second cantilever spring contacts anchored to spaced fixed points and extending toward each other, in the general direction of a line joining said points, with their free ends in proximity; a third contact situated between the free ends of said first and second contacts, said third contact having a pair of contact surfaces facing in opposite directions substantially normal to said first and second contacts and having a neutral position in which said contact surfaces are engaged by free ends of said first and second contacts; and means for displacing said third contact in a direction substantially normal to said first and second spring contacts until electrical contact with one of said first and second contacts is broken said first, second and third contacts being extensions of the center conductors of three separate coaxial lines.

2. Apparatus as claimed in claim 1 in which there are provided fourth and fifth fixed contacts, said fourth fixed contact being on the same side of said first contact as the associated contact surface of said third contact and said fifth contact being on the same side of said second contact as the associated contact surface of said third contact, said fourth and fifth contacts being in engagement with said first and second contacts, respectively, when said third contact is in its neutral position.

3. Apparatus as claimed in claim 2 in which said first and second spring contacts are biased toward the respective surfaces of said third contact which they engage.

4. A switching device for coaxial transmission lines comprising first and second cantilever spring contacts anchored to spaced fixed points and extending toward each other, in the general direction of a line joining said points, with their free ends overlapping, a third contact situated between the overlapping ends of said first and second contacts and having a neutral position in which it makes electrical contact with both said first and second contacts, and means for displacing said third contact in a direction substantially normal to said first and second contacts until electrical contact with one of said first and second contacts is broken said first, second and third contacts being extensions of the center conductors of three separate coaxial lines.

5. Apparatus as claimed in claim 4 in which there are provided a pair of fixed contacts positioned on opposite sides of the overlapping portion of said first and second contacts and on the same sides of said first and second

spring contacts as said third contact, one of said fixed contacts being in electrical contact with said first contact and the other being in electrical contact with said second contact when said third contact is in its neutral position.

6. Apparatus as claimed in claim 5 in which said first and second cantilever spring contacts are biased toward said third contact.

7. Apparatus as claimed in claim 1 in which the last named means comprises a coil, means for energizing said coil with alternating current for producing an alternating magnetic field, and means responsive to said alternating field for oscillating said third contact about its neutral position in a direction substantially normal to said first and second contacts.

8. Apparatus as claimed in claim 4 in which the last named means comprises a coil, means for energizing said coil with alternating current for producing an alternating magnetic field, and means responsive to said alternating field for oscillating said third contact about its neutral position in a direction substantially normal to said first and second contacts.

9. A switching device comprising first and second cantilever spring contacts anchored to spaced fixed points and extending toward each other with their free ends overlapping, a third cantilever contact anchored to a fixed point and having its free end situated between the overlapping ends of said first and second contacts and having a neutral position in which it makes electrical contact with both said first and said second contacts, a pair of fixed contacts positioned on opposite sides of the overlapping portion of said first and second contacts and on the same sides of said first and second contacts as said third contact, one of said fixed contacts being in electrical contact with said first contact and the other being in electrical contact with said second contact when said third contact is in its neutral position, and means situated on the opposite side of said first and second contacts with respect to said third contact anchor point for oscillating said third contact about its neutral position in a direction substantially normal to said first and second contacts, said oscillating means comprising an elongated armature element pivoted at a point between its ends and having a spring biased neutral position in which it is in alignment with said third contact in its neutral position, an insulating mechanical coupling between one end of said armature and said third contact, a permanent magnet having two poles located adjacent to the other end of said armature and on either side of the longitudinal axis of said armature in its neutral position, a fixed coil surrounding said armature between said pivot point and said other end, and means for applying alternating current energization to said coil.

10. An electromechanical oscillatory drive comprising an elongated armature of high magnetic permeability, a torsion bar made of an elastic metal and having a right angle cross section, means anchoring the outer ends of said torsion bar, means for rigidly attaching said armature at a point intermediate its ends to said bar in a transverse direction, fixed permanent magnet means having its poles adjacent one end of said armature and located equal distances on either side of the longitudinal axis of said armature when said torsion bar is unstressed, a fixed coil surrounding said armature between said torsion bar and said one end, and means for applying alternating current energization to said coil.

11. A rhombic antenna lobe switch operating to periodically interchange the feed and terminating points of the antenna, said switch comprising first and second cantilever spring contacts anchored to spaced fixed points and extending toward each other with their free ends overlapping, a third contact situated between the overlapping ends of said first and second contacts and having a neutral position in which it makes electrical contact with both said first and second contacts, said first and second spring contacts being biased toward said third

contact, a pair of fixed contacts positioned on opposite sides of the overlapping portion of said first and second contacts and on the same sides of said first and second contacts as said third contact, one of said fixed contacts being in electrical contact with said first contact and the other being in electrical contact with said second contact when said third contact is in its neutral position, means for oscillating said third contact about its neutral position in a direction substantially normal to said first and second contacts, equal terminating resistances connected between said fixed contacts and the ground for said antenna, means for connecting the feed point of said antenna to one of said first and second contacts and the terminating point of said antenna to the other of said first and second contacts, and means for connecting an external circuit to said third contact.

12. A rhombic antenna lobe switch operating to periodically interchange the feed and terminating points of the antenna, said switch comprising: a body of conductive material, said body being at the potential of the antenna ground; a first bore extending through said body; second and third bores extending into said body from opposite directions and intersecting said first bore, the axes of said second and third bores being parallel to each other, being in a plane normal to the axis of said first bore and being slightly offset from said third bore axis by equal amounts in opposite directions; means for attaching a first coaxial transmission line serving as an external circuit, a second coaxial transmission line having its center conductor connected to the feed point of said antenna and a third coaxial transmission line having its center conductor connected to the terminating point of said antenna, to said body so that said first, second and third bores, respectively, form extensions of the inner surfaces of the outer conductors of said lines; first and second cantilever spring contacts attached to the center conductors of said second and third transmission lines and extending toward each other through said second and third bores with their free ends overlapping; a third contact, having a thickness substantially equal to the sum of said offsets, situated between the overlapping ends of said first and second contacts, said third contact extending through a portion of said first bore and being flexibly attached to the center conductor of said first transmission line for movement in a direction normal to the axes of said second and third bores and having a neutral position in which it makes electrical contact with both said first and second contacts; a pair of fixed contacts positioned on opposite sides of the overlapping portion of said first and second contacts and on the same side of said first and second contacts as said third contact, one of said fixed contacts being in electrical contact with said first contact and the other being in electrical contact with said second contact when said third contact is in its neutral position; equal terminating resistances connected between said fixed contacts and said body; and means extending through that part of said first bore not containing said third contact for oscillating said third contact about its neutral position in a direction normal to the axes of said second and third bores.

13. Apparatus as claimed in claim 12 in which each of said fixed contacts is attached to said body by means of a resistive material providing the terminating resistance.
